UNITED STATES PATENT OFFICE

GLEN L. POPE AND ABE COHEN, OF OMAHA, NEBRASKA

BUTCHER'S APRON AND FASTENERS THEREFOR

Application filed July 12, 1928, Serial No. 292,088. Renewed November 25, 1929.

This invention relates to an improvement in aprons and particularly to aprons worn by butchers or others and which require frequent laundering.

5 One object of the invention is to provide means which will be convenient in use for securing the apron to the body of the wearer. Another object is to provide such an arrangement of parts that the tie-strings will not be 10 come detached or torn from the apron during the operation of laundering. Still another object is to provide fabric fasteners for the removable hooks of the apron which will lie comparatively flat when ironed and will not 15 present the appearance of a pad or roll. Also the invention includes a reduced part for the neckband, to prevent buckling or injury to said band during the operation of laundering.

With the foregoing objects in view, the invention presents a new and useful construction, combination and arrangement of parts as described and claimed herein, and as shown in the accompanying drawing, it being understood that changes may be made in form, 25 size, proportion and minor details, said changes being determined by the scope of the invention as claimed.

In the drawing, Fig. 1 is a view showing the front of the apron with parts extended. 30 Fig. 2 is a detail showing a roll or fold for the neck band. Fig. 3 is a broken away detail showing the rear side of the apron provided with loops to facilitate laundering. Fig. 4 is a sectional detail showing a mounting for 35 a removable hook. Fig. 5 is a detail view showing a fabric fastener. Fig. 6 is a section on line 6—6 of Fig. 2.

Referring now to the drawing for a more particular description, the invention is shown 40 and described in connection with an apron 6 provided with a neck band 7 of loop-form at its upper end and having a pair of opposed tie-strings 8 and 8', this apron being the kind generally used by butchers, the strings extending entirely around the body and secured 45 together at the front or tied together at the back after the band 7 has encircled the neck of the wearer.

In order that these aprons may be washed 50 and ironed it is necessary that any metallic

parts used as fastening devices be removed, and therefore each tie-string is provided at its rear side near its end with a hook 9 which may be readily removed since they are mounted in eyelets 10 which are formed in said 55 strings.

The particular hooks and their mounting thus mentioned are not claimed as a part of the present application but are shown, described and claimed in a pending companion 60 application for Letters Patent Serial No. 286,458, Patent No. 1,700,594, dated January 29, 1929.

We provide a pair of elongated flexible fastener-members indicated respectively at 65 11 and 12 each consisting of a strip of tape wound spirally to provide holder-wings or pockets 13 for receiving the prong 14 of a hook, said pockets being disposed in spaced relation at longitudinal intervals of a fastening-member. Numerals 15 indicate rows of stitches for securing the loops of the spirally disposed tape of each fastener-member to a fabric strip 16, and each strip 16 is secured to the apron, at its front side, by 70 75 rows of stitches 17.

The fastener-members thus described, when the apron is laundered, will lie flat upon the fabric of the apron for the reason that the loops are disposed in spaced relation, 80 and therefore these members will be comparatively thin, and when the apron is laundered they will not be obtrusive and will avoid the appearance of rolls or pads.

In operation after the neck band has been 85 placed to encircle the neck, the apron will be disposed to cover the front part of the body. The wearer then draws the apron string 8 around the back to attach it to the fastener 12, the apron string 8' being moved in a reverse direction to be attached to the fastener-member 11, the hooks 9 carried by the respective tie-strings each engaging in a selected pocket 13 of a fastening-member 11 and 12. 90

The act of placing the apron in operative 95 position as described may be conveniently and readily performed, and the apron will suitably fit the body of the wearer, the prongs 14 engaging in the selected pockets mentioned for a loose or close fit, as may be de- 100

sired, this arrangement, as is obvious, being of advantage, and more convenient than knotting the strings.

In order that the tie-strings will not become torn or detached from the apron during the operation of laundering, and that they will not become buckled, loops 18 are provided for receiving the strings, these loops being secured to that part of the apron at intervals between the inner end of the tie-strings and neck band, at the rear side thereof, and for the purpose of preventing injury to the strings and prevent detachment thereof from the apron during the operation of washing and while moving through the mangle the apron strings are placed in said loops 18, and since the part of the apron to first enter the mangle is its bottom, the strings will be pressed upon the fabric of the apron while held within the loops 18, and will be protected from injury.

Also in order that the neck band 7 will not become buckled or injured while the apron is moving through the mangle, its middle part is formed as a roll 19, this being accomplished simply by folding this band upon itself transversely and connecting the parts by stitches 20. Since this reduced part 19 is approximately of rope-form it will not become injured when the apron moves through the mangle, and the remaining parts of the neck band will be permitted to remain in a flat condition while pressed by the mangle and buckling or injury, by reason of this construction, may be avoided.

By referring to Fig. 4 of the drawing it will be seen that the tie-strings of the apron are of such construction that the metallic hooks 9 will be entirely concealed when the apron is in use, each tie-string being formed as a sheath, the inner strip 21 being provided with eyelets 10 for receiving the shanks of the hooks and the outer strip 22 operating to cover said hooks so that they will not be obtrusive.

We claim as our invention,—

1. An improved apron having a pair of tie-strings extending from its opposed edges, a pair of fabric fastener-members attached to the front of the apron, and a pair of hooks each adapted to be removably mounted in a tie-string for engagement with a fastener-member.

2. An improvement in an apron having a pair of tie-strings provided with eyelets and attached to its opposed edges, a pair of elongated, fabric fastener-members each secured to the front of the apron equi-distant from said opposed edges of the apron, and a pair of metallic hooks each adapted to be removably mounted in the eyelets of the tie-strings for engaging a fastener-member.

3. An improved apron having a pair of tie-strings each including an outer and an inner fabric strip and having a pair of eyelets

formed in its inner strip near its outer end, said tie-strings being secured at their inner ends to opposed edges of the apron, a fastener-member secured to the apron at the front part thereof, and metallic hooks removably disposed in the eyelets for engaging the fastener-member.

In testimony whereof, we have affixed our signatures.

GLEN L. POPE.
ABE COHEN.
